COLD PRESS

William L. Clouse, Tiffin, Ohio, assignor to The
National Machinery Company, Tiffin, Ohio

Application April 1, 1931, Serial No. 526,991

6 Claims. (Cl. 78—39)

This invention relates to a cold press of the vertical type designed for striking one or more blows in the formation of a forging.

Cold presses for making large forgings are in use but without exception their construction has been such that the production of well finished forgings, as in coining has been impossible. One reason for failure has been the fact that presses have been provided with built up frames incapable of preventing the "weaving" or swaying motion both laterally and from front to rear which has been especially pronounced when the forging being produced is of varying thickness and subjects the heading die to unequal resistances at different points.

Sectional frames the members of which are fastened together have also been objectionable because, in large presses in which heavy forgings are produced, the excessive resistance to the action of the slide causes an extensive stretch of the tying means and the frame.

A still further objection which is present in large vertical presses now in use is the employment of knuckles or toggles for actuating the slide. A toggle connection tends to slow down the slide as it approaches the lower limit of its movement. This prevents the rapid compression of the blank so essential to the proper shaping of the forging.

In order to produce a properly finished forging it is necessary that there be no movement in the bed frame and no resiliency in the connection between the slide and its driving mechanism. If the frame of the machine sways or "weaves" in any direction or if the frame stretches while the blank is under compression, the dies will not be brought into proper relation to each other to insure flow of metal into all portions of the cavities in the dies. On the contrary, metal which should be forced into these cavities will follow the path of least resistance which is the excessive space produced between the sides of the dies through the failure of the dies to properly come together. The metal, flowing through this space, forms a flash of objectionable proportions and where angular or rounded corners, shoulders, etc., should be formed on the finished forging, there will be found a lack of metal resulting in an article of incorrect shape.

All of the foregoing objections have been present heretofore in cold presses due to the fact that none of them have been so built as to resist "weaving" or swaying in all directions and to resist stretching. Consequently it has not been possible, until now, to produce in such a press

from hot, semi-hot or cold blanks, an accurately finished forging of irregular shape and of large size.

Another objection to present types of cold presses is found in the use of toggles or links for operating the large slides required. As heretofore pointed out, a driving connection of this kind slows down the movement of the slide as it reaches its lower limit. Consequently when the blank is placed under heavy compression during the formation of the forging, the metal of the blank, during this slowing down of the slide, will exude from between the dies and thus form a heavy flashing composed of metal which should have gone to the pockets in the dies to properly shape the forging.

Other presses of large sizes have used cranks with special connecting elements between them and the slide, but the resiliency present in these connections has resulted in failure to properly and quickly confine the metal under compression and insure filling of all portions of the die cavities. Consequently imperfect articles have been produced.

It is an object of the present invention to provide a vertical press in which none of the objections herein stated are present.

It is a further object to so construct the frame of the press that it cannot sway or "weave" in any direction relative to the bed supporting the stationary die.

Another object is to provide a vertical press having its frame formed in a single steel casting reinforced by tie rods which are shrunk there-in so as to be constantly under tension, it therefore being impossible for the frame to stretch during the formation of large forgings because before the stretching action could occur it would first be necessary to overcome the tension of the rods due to contraction and thereafter overcome the natural resistance offered by both the one-piece steel frame and the rods.

A still further object is to provide a vertical press having means for bringing the movable die quickly to closed position on the stationary die so that, during the compressing action the metal of the blank will have no opportunity to exude from between the dies. On the contrary the metal must be forced into all portions of the die cavity, thereby producing a finished article shaped accurately to the form and smoothness desired.

Large vertical presses heretofore constructed have required the use of adjustable connections between the slide and its operating means. These connections have been used for the purpose of

insuring proper cooperation of the movable die with the fixed die and to enable the dies to be separated should they become jammed by the work.

5 One of the objects of the present invention is to eliminate all adjustments between the slide and its driving means so that there are no connections likely to spring or become otherwise distorted when subjected to excessive resistance during the forging operation.

10 A still further object is to provide a bed frame having a novel arrangement of openings whereby the stationary and movable dies of the press can be accommodated properly. It is not new in 15 cold presses of the vertical type to arrange stationary and movable dies in the bed frame but under some conditions the dies and the work therebetween have become jammed while the operating mechanism is on a dead center. Consequently it has been extremely difficult to correct the trouble and again start the machine. One of the objects of the present invention is to 20 so mount the stationary die that, in the event of the parts becoming jammed, it will be possible readily to release them so that the operation of the machine can be promptly proceeded with.

Another object of the present invention is to 30 provide a cold press of the vertical type having a slide for carrying the movable die, this slide being so constructed and so assembled relative to its operating means as to permit the use of a bed frame of much less height than would otherwise be required.

35 A still further object is to provide a slide having widely spaced bearing surfaces for engaging guides provided therefor in the bed frame so that the slide and the die carried thereby will have an accurate right line movement.

40 A still further object is to provide a bed frame which does not require the use of the usual capped bearings for the main crank shaft of the machine but can utilize bearings which are housed within the bed frame.

45 With the foregoing and other objects in view which will appear as the description proceeds, the invention resides in the combination and arrangement of parts and in the details of construction hereinafter described and claimed, it 50 being understood that changes in the precise embodiment of the invention herein disclosed, may be made within the scope of what is claimed, without departing from the spirit of the invention.

55 In the accompanying drawings, the preferred form of the invention has been shown.

In said drawings:

Figure 1 is a front elevation of the press.

Figure 2 is a side elevation thereof.

60 Figure 3 is a section on line 3—3, Figure 1, the slide and supporting wedge being shown in elevation.

Figure 4 is a top plan view.

Figure 5 is a section on line 5—5, Figure 3.

65 Figure 6 is a section on line 6—6, Figure 3.

Figure 7 is a section on line 7—7, Figure 3, the wedge being shown in elevation.

Figure 8 is a perspective view of the wedge.

Figure 9 is a section on line 9—9, Figure 7.

70 Figure 10 is a perspective view of the slide.

Referring to the figures by characters of reference, 1 designates the bed frame of the press formed in a single casting the flanged base 2 of which is reinforced by an integral transverse segmental extension 3 extending at its ends be-

tween depending bosses 4. These bosses are in line with similar ones located at the top of the bed frame as shown at 5 where they are disposed at opposite sides of a reinforcing segmental extension 6 formed integral with the bed frame. 5 This extension as well as the extension 3 is arranged transversely of the frame as shown. Tension rods 7 are extended longitudinally within the bed frame and seated at their ends within the bosses 4 and 5 where they are held by any 10 means desired. These rods are shrunk in the bed frame so as to be constantly under tension thereby to add materially to the tensile strength of the bed frame.

The sides of the bed frame 1 can be formed 15 with openings 8 of sufficient size to receive the crank shaft 9 which, in the structure illustrated, carries an eccentric 10. This shaft is insertible endwise into position and supports the eccentric between said openings. The shaft is journaled 20 in bushings 11 carried by the upper and lower bearing blocks 12 and 13. Blocks 12 are adapted to thrust upwardly against the top walls of the openings 8 while the blocks 13 are adjustably supported by wedges 14 which can be forced between 25 them and the bottom walls of the openings 8 and subsequently held by any suitable means if so desired. For example, a plate 15 can be bolted to the bed frame so as to lap the wedge 14. A screw 16 can be mounted in this plate and, 30 when adjusted against the wedge 14, will hold said wedge against accidental displacement.

Any suitable means can be provided for actuating the shaft 9. For example, a gear 17 can be secured thereto where it will mesh with and 35 be actuated by a gear 18 secured to a countershaft 19. This countershaft can be journaled in bearings 20 provided therefor at the back portion of the bed frame 1 or, if preferred, can be journaled in capped bearings such as commonly used. 40 Another gear 21 can be secured to shaft 19 adjacent to that side of the machine remote from gear 18 and can mesh with the gear 22 of an electric motor 23. This motor can be connected to the back portion of the bed frame or can be 45 supported by any other suitable means. Any preferred means other than an electric motor could be employed for driving shaft 19. A fly wheel 24 is secured to shaft 19.

The bed frame 1 has its side portions connected 50 by the integral base 2 and the integral crown portion 25 on which is formed the segmental reinforcing extension 6. This crown portion is extended downwardly back of the openings 8 as shown particularly in Figure 3 to provide a recess in the upper portion of the bed frame between the sides thereof and, as a further means for reinforcement, the side portions may be connected by an integral cross bar 26 cored to receive the shaft 19 as shown at 27 in Figure 3. The 55 recess thus provided constitutes a housing for the shaft 9 and eccentric 10 which are supported by the bearings in the sides of the bed frame.

In the construction of the bed frame as herein pointed out it has been the purpose to so arrange the integral parts of the frame as to resist every tendency of said frame to "weave" or sway in any direction. For example, the heavy side portions of the bed frame 1 are joined at the top not only by the reinforcing extension 6 but 70 also by the rearwardly and downwardly curved crown portion 25 which cooperates with the sides of the frame and the extension 6 to form in effect a one-piece box which tends to resist all tendencies to sway. In addition to this box-like 75

construction there is provided the cored bar 26 which is integral with the sides of the bed frame and acts to further resist the lateral "weaving" or swaying of the bed frame. Stretching of the frame is of course resisted by the tensioned bars 7 which, as heretofore stated, are shrunk into the frame.

The front of the crown portion 25 of the bed frame is recessed as shown at 28. Along the back 10 of this recess are provided spaced longitudinal slide bearings 29. Thus there is provided an upper guide channel with back and sides formed by the bed frame. A combined guide and retaining plate 30 is secured across the recess or 15 channel 28 and cooperates with the bearings 29 to form a guide-way for the upper portion of a slide as hereinafter explained.

Formed on the inner faces of the sides of the bed frame adjacent the rear portions thereof and 20 below the level of the openings 8 are laterally spaced longitudinal slide bearings 31. These bearings, with adjacent portions of the bed frame, provide a lower guide channel and secured in recesses 32 provided therefor in the front faces of 25 the sides of bed frame 1, are angular strips 33 which extend back between the sides of the bed frame in front of the bearings 31 so as to cooperate with said bearings to properly guide the lower portion of a slide. These angle or guide 30 strips 33 can be connected by one or more cross bars 34 bolted or otherwise fastened to them.

Slidable between the bearings 31 and strips 33 is the large lower end or main portion 35 of the slide of the machine. This lower portion has a 35 recess 36 extending therewith from the top and back faces thereof and the side walls of this recess are formed with openings 37. Extending downwardly into the recess is the lower portion of a pitman 38 which is carried by the eccentric 40 10 so as to be actuated thereby. A pin 39 is seated in the pitman and bears in the openings 37.

Slidably engaging the bearings 29 and plate 30 is the smaller upper end or steadyng portion 45 40 of the slide. This is preferably formed hollow so as to be open at the back. An intermediate connecting portion 41 is offset from and cast integral with the lower and upper portions 35 and 40 of the slide and is channeled longitudinally as 50 indicated at 42, the ends of the channel opening into the respective end portions 35 and 40 of the slide. Thus this intermediate portion can embrace a portion of the eccentric 10 and pitman 38 as shown particularly in Figure 3 thereby 55 making it possible to produce a very compact structure.

As the bearings 29 and 31 as well as the additional bearings provided by the plates or strips 30 and 33 are accurately finished and positioned 60 and as those faces of the slide cooperating therewith are accurately machined, it will be apparent that the slide will have an accurate right line movement. By utilizing the widely spaced end portions 35 and 40 for engaging the bearings, the slide is prevented from tilting out of proper alignment. This result has been possible heretofore solely by employing a long slide all parts of which 65 have been located beneath the operating shaft. Consequently in a machine having the same length of stroke and the same power as the one herein described it has not been possible to provide a structure less than ten or twelve feet in height from the floor line to the pitman shaft, whereas in the present device the maximum distance between the floor line and said shaft 9

need not be more than six feet six inches. As will be appreciated by those skilled in this art, it would be impractical to build a machine with a one-piece bed frame where the distance between the floor line and the pitman shaft is ten or twelve feet. Applicant, however, by utilizing a slide such as herein described can reduce said distance to approximately six feet and is thus enabled to utilize a one-piece bed frame. Furthermore the structure of applicant's press provides a longer path of travel for the slide than would be practically possible in any vertical cold press approximating the power of the one herein disclosed. As the fronts of the bed frame and of the guides 29 and 31 are open it will be obvious 15 that the slide can be assembled readily with the bed frame by suspending it close to and in front of the bed frame, connecting the pitman 38 to the main portion 35 of the slide, and then moving the slide and pitman back into the bed frame 20 where the slide will properly engage the guides as shown in Figure 3. Thereafter the cover plates 30 and 33 can be placed in position to hold the slide in proper operative relation with the guides.

The lower end of the slide can be provided with 25 any suitable means for attaching a movable die to it. For example, and as shown in the drawings, a dove-tail channel 42 can be formed in the lower face of the slide for the reception of the dovetailed portion 43 of a die plate 44. The 30 die 45 is carried by this plate. An ear 46 can be extended downwardly from the slide to receive an adjusting screw 47 which engages the die plate 44. Thus by rotating this screw the plate can be shifted forwardly or backwardly relative to 35 the slide and thereby cause a corresponding adjustment of the movable die 45. Obviously means other than that shown and described may be employed for connecting the die to the slide.

The base of the bed frame is formed with an 40 inclined upper face 43 which is provided, in its highest portion, with a central longitudinal channel 49 which is substantially horizontal. The inclined surface or seat 48 supports a flat wedge 50 having a central longitudinal tongue 51 formed 45 upon the bottom surface of the thinnest portion thereof and projecting therefrom. This tongue is slidably seated in the channel 49. The upper surface of the wedge is horizontal and is adapted to support the stationary die used in the press. 50 This die can be held adjustably by any suitable means. For example, a dovetail groove 52 can be extended transversely within the wedge to receive a dovetail die plate carrying the stationary die 54. A screw 55 can be swiveled in an ear 55 56 at one end of groove 52 and can engage the die plate. Thus by means of this screw the die 54 can be adjusted transversely of the machine. This adjustment together with the front and back adjustment of die 54 enables the operator 60 to accurately match the two dies prior to the operation of the machine.

The large end of the wedge 50 is engaged by an adjusting screw 56 which is carried by an ear 57 extending from the inclined seat 48. By means 65 of this screw the wedge can be shifted longitudinally to raise the die 54 relative to the slide and thereby insure proper relative positioning of the two dies when the slide reaches the lower 70 limit of its stroke.

In order to prevent accident displacement of the wedge after it has been adjusted, bolts 58 can be seated in longitudinal slots 59 formed in the corner portions of the wedge and also in cor- 75

responding openings or slots 60 formed in the base 2.

As heretofore stated this press can be used for making forgings of different sizes and shapes 5 and will produce them accurately and with well finished surfaces. After the blank, whether it be hot, semi-hot or cold, has been placed above the stationary die the slide is actuated by eccentric 10 which will drive it rapidly until the movable die is brought to its extreme lowermost position. As the frame of the machine can neither stretch, "weave" nor sway because of its peculiar construction, and as there is no objectionable retardation of the downward movement of the slide 15 and its die, there will be no excessive flow of metal between the dies which was intended to be forced into the cavities for the purpose of producing a forging of the required shape and size. Instead the resultant forging will be well finished 20 and all portions thereof will be properly built out.

When forgings of irregular thicknesses have been produced in vertical presses it has generally been necessary to so arrange the dies relative to the central line of pressure that the resistance 25 to compression offered by different portions of the blank would be equalized so as to offset, if possible, any tendency of the bed frame to sway to an excessive degree. The proper positioning of the dies for this purpose has been practically impossible. By constructing the bed frame as shown 30 and described by me no such careful placing of the dies is necessary because the proportions of the frame are such as to overcome any tendency of the frame to "weave" even though the resistance to the action of the movable die should be unequal.

While the wedge 50 is used for adjusting the stationary die upwardly and downwardly, a very important function thereof resides in its utility 40 as a relief device. Frequently, in the operation of a cold press the dies and the work become jammed while on or close to a dead center so that it becomes impossible to continue operation of the machine without taking down some of the parts. 45 In the present case, should the work become jammed and the machine stop, it will be necessary only to disengage screw 36 from the wedge and, after loosening bolts 38, to strike a blow with a sledge against the end of tongue 51. This 50 will drive the wedge a short distance downwardly along the inclined surface 48 and release the jammed portions so that the slide can be raised, the parts quickly readjusted and the operation continued. It has been found in practice, that 55 in order to obtain this desirable relief, it is essential that the angle of the wedge be not less than ten degrees. Otherwise this wedge, which in a machine of the present type can be approximately twenty-nine inches wide and forty-seven 60 inches long, or larger, could not be unseated by means of a sledge. This large pitch of the wedge is also advantageous because of the extensive adjustment of the die which is possible as a result thereof but which would not be possible in other known types of cold presses without materially 65 reducing the vertical height of the dies which, of course, would be decidedly objectionable.

As a means for expediting cleaning of the cavity in the bed frame containing the dies, side 70 openings 61 can be formed in the sides of the bed frame adjacent to the wedge as shown in Figures 2, 3 and 7. Thus dirt, small pieces of metal and other accumulations can be easily brushed or blown from the lower portion of the bed frame and at the same time access is given

to any adjusting means which might be provided for the stationary die. The openings also allow the operator to readily introduce or remove the work. It is to be understood, of course, that one or both of these openings may be dispensed with 5 if so desired.

What is claimed is:

1. In a cold press a one-piece solid frame, a shaft extending through the frame, a guide above the shaft having an integral back and sides forming an upper guide channel, a guide below the shaft having an integral back and sides forming a lower guide channel, a die carrying slide having a main portion adapted to reciprocate in the lower guide channel, and an upper steadyng portion adapted to reciprocate in the upper guide channel, said portions being connected by an integral intermediate connecting portion passing one side of the shaft, cover plates for the channels, and a driving connection between the main 20 portion of the slide and the shaft thereabove.

2. In a cold press a one-piece solid frame, a shaft extending through the frame, a guide above the shaft having an integral back and sides forming an upper guide channel, a guide below the shaft having an integral back and sides forming a lower guide channel, a die carrying slide having a main portion adapted to reciprocate in the lower guide channel, and an upper steadyng portion adapted to reciprocate in the upper guide channel, 25 said portions being connected by an integral intermediate connecting portion passing one side of the shaft, cover plates for the channels, and a driving connection between the main portion of the slide and the shaft thereabove, said intermediate connecting portion being channelled to receive a portion of the driving connection.

3. A cold press including a one-piece frame open at the front, upper and lower guides within the frame, a shaft journaled in the sides of the 40 frame, a one-piece slide comprising a lower main portion, an upper steadyng portion and an intermediate connecting portion, said main and steadyng portions being mounted for reciprocation upon the lower and upper guides respectively, 45 a driving pitman connection between the shaft and the main portion of the slide, said guides opening forwardly within the frame to permit backward movement of the connected pitman and slide into the frame and into operative relation 50 with the guides, and cover plates for holding the slide to the guides.

4. In a cold press a bed frame formed in a single casting including an anvil supporting base, a top overlying the base, and side portions integral 55 with the top and base and extending from front to back thereof, said top extending rearwardly and downwardly and cooperating with the side portions to form a one-piece box-like upper portion of the bed frame for holding said frame 60 against lateral weaving, there being openings extending through the side portions of a diameter sufficient to permit the longitudinal insertion of a shaft and a crank thereon through the openings to position the crank between the top and base 65 and between the side portions.

5. In a cold press a bed frame formed in a single casting including an anvil supporting base, a top overlying the base, and side portions integral 70 with the top and base and extending from front to back thereof, said top extending rearwardly and downwardly and cooperating with the side portions to form a one-piece box-like upper portion of the bed frame for holding said frame

against lateral weaving, there being openings extending through the side portions of a diameter sufficient to permit the longitudinal insertion of a shaft and a crank thereon through the openings to position the crank between the top and base and between the side portions, there being a guide member formed by the top above the openings in the side portions and a guide member formed by the back and side portions below said openings, 10 and a slide for engagement with said guide members.

6. In a cold press a bed frame formed in a single casting including an anvil supporting base, a top overlying the base, side portions integral 15 with the top and base and extending from front to back thereof, said top extending rearwardly and downwardly and cooperating with the side portions to form a one-piece box-like upper portion of the bed frame for holding said frame

against lateral weaving, there being openings extending through the side portions of a diameter sufficient to permit the longitudinal insertion of a shaft and a crank thereon through the openings to position the crank between the top and base and between the side portions, there being a guide member formed by the top above the openings in the side portions and a guide member formed by the back and side portions below said openings, 10 said guide portions being adapted to be engaged by an upper steadyng portion and a die carrying portion respectively of a slide insertible backwardly between the side portions, and means detachably connected to the top and side portions of the bed frame for holding the adjacent portions 15 of a slide in working engagement with the respective guide portions.

WILLIAM L. CLOUSE.
